FENDER FOR AN AUTOMOBILE

Joseph R. Schemansky, Birmingham, Mich., assignor to
General Motors Corporation, Detroit, Mich., a corpora-
tion of Delaware

Application February 14, 1957, Serial No. 44,871

Term of patent 7 years

(Cl. D14—6)

Figure 1 is a side elevational view of a fender for an automobile embodying my new design;

Figure 2 is a top plan view;

Figure 3 is a rear elevational view taken along the plane indicated by line 3—3 of Figure 1;

Figure 4 is a sectional view taken along the plane indicated by line 4—4 of Figure 1; and

Figure 5 is an enlarged view of a portion of Figure 4.
The portions of the automobile shown by means of broken lines are disclosed for illustrative purposes only.

I claim:

The ornamental design for a fender for an automobile, substantially as shown and described.
